ELECTRON DISCHARGE DEVICE EMPLOYING
CAVITY RESONATORSLeon S. Nergaard, Princeton, N. J., assignor to
Radio Corporation of America, a corporation
of Delaware

Application December 14, 1943, Serial No. 514,206

8 Claims. (Cl. 315—5)

1

My invention relates to electron discharge devices and circuits therefor and particularly to such devices and circuits useful at ultra high frequencies.

Electron discharge devices using cavity resonators are used at ultra high frequencies. In the triode type, the electrodes are usually arranged in the order of cathode, grid and anode, and may have radially directed supports and lead-ins extending through the envelope and contacting the cavity resonator circuits. For example, in the triode an input cavity resonator, which may be of the coaxial line type, is connected between the cathode and grid, and the output resonator is connected between the grid and anode. In another type of tube referred to as an inductive output tube, the electrodes are in the order of cathode, grid, accelerator and collector. The input resonator, usually of the coaxial line type, is connected between the cathode and grid, a second resonator is connected between the grid and accelerator, and the output resonator is positioned between the accelerator and collector. The resonator connected between the control grid and accelerator or screen is used to bring the accelerator to cathode potential for radio frequencies and is used for regeneration to compensate for the diode loading.

At ultra high frequency it is desirable to so construct and arrange the leads to tube electrodes that they have as low inductance as possible, or, alternatively, to so arrange them that they comprise conductors of transmission lines which may be joined with an external circuit. Leads of triodes and of the triode section of inductive output tubes have been brought out in the same space sequence as the electrodes have within the tube, namely the sequence cathode, grid and anode, or in the case of the inductive output tube, the accelerator and collector. Because of this arrangement it is necessary to use the so-called grounded grid circuit, which is characterized by having a circuit between the grid and plate, or grid and accelerator. The disadvantages of this arrangement are, first, the full diode loading of the tube appears across the input circuit. This requires a higher driving power and results in a lower power gain. Second, in the inductive output tube the circuit between the grid and accelerator is used to bring the accelerator to cathode potential as far as radio frequency is concerned, or to introduce regeneration to compensate for the diode loading. Because regeneration tends to be unstable, tuning of the circuit is critical. It is desirable to eliminate diode loading and to remove

2

the circuit between grid and accelerator. This would simplify tuning of the tube circuit without sacrificing performance.

It is, therefore, the principal object of my invention to provide an improved form of an electron discharge device and circuit useful at ultra high frequencies.

It is another object of my invention to provide such a device utilizing cavity resonators but in which the usual diode loading associated with tubes of this type is eliminated, and in which circuits requiring critical tuning are made unnecessary.

It is a further object of my invention to provide such a device utilizing cavity resonator circuits in which the grounded grid circuit is avoided.

The novel features which I believe to be characteristic of my invention are set forth with particularity in the appended claims, but the invention itself will best be understood by reference to the following description taken in connection with the accompanying drawing in which Figure 1 is a longitudinal section of an electron discharge device and its associated circuit made according to my invention, Figure 2 is an end view of the cathode of the device shown in Figure 1, Figure 3 is an end view of the cathode and grid of the device shown in Figure 1, and Figure 4 is a diagram showing an equivalent circuit of the device shown in Figure 1.

To overcome the objections above to the usual lead arrangement, I have devised a structure in which the usual lead sequence is changed to the sequence grid, cathode, anode or accelerator, thus permitting the use of grounded cathode circuits. An example of such a device and circuit is shown in Figure 1.

Referring to Figure 1 I show an elongated evacuated envelope 10 containing at one end an indirectly heated cathode 11 followed by grid 12 and accelerator 13, a second accelerator 14 and a collector 15 provided with cooling fins 16 and secondary electron emission suppressor ring 17, the collector being supported by leads 15' and the suppressor by lead 17'. The suppressor is maintained during operation of the device at a lower potential than the collector.

The indirectly heated cathode 11 is provided with a shielding and focusing collar 18 from which the cathode 11 is supported by means of the radially extending support wires 11' as shown in Figures 1 and 2. A radially directed support and lead 19 which may be a ring is sealed through the envelope 10 and supports the cathode collar 18 and the cathode 11 in position within the en-

velope. The cathode is also provided with a plurality of leads, such as 20, which extend through the base of the envelope of the tube, one of the leads 21 serving as a heater lead for the cathode, the other side of the cathode heater being connected through the support wires 11', collar 18 and support 19 to the outside of the envelope. The lead 21 is so placed that interaction between it and the fields within the resonator are reduced to a minimum.

The grid as shown in Figures 1 and 3 comprises a ring-shaped member 12' supporting a plurality of transverse wires or mesh. This grid has support wires 22 extending through the space between the cathode 11 and the collar 18 and through the press of the envelope. Thus the grid and cathode leads cross each other.

The accelerator 13 is supported by a ring-shaped lead-in and support member 13' also sealed through the envelope of the tube.

It will, therefore, be seen that the leads for the electrodes are now in the order of grid leads 22, cathode lead 19 and accelerator lead 13'.

The input circuit comprises a coaxial line type resonator comprising an inner tubular member 25 and outer tubular member 26 and closed at the outer end by means of the disc 27. The inner tubular member 25 is capacitively coupled to the grid leads 22 by means of the collar 22' fixed to and connected to the grid leads and insulated from the inner tubular member by the insulating collar 28, preferably of mica. The other end of the input resonator circuit is connected to the cathode lead 19 by means of resilient spring type fingers 30 secured to a radially extending wall 29 at the inner end of the resonator. The input signal is provided by means of the coupling loop 31.

The output resonator 32 is positioned between the accelerator 13 and accelerator 14 and functions in a manner now well known, as described in Haeff Patent 2,237,878. The accelerator or screen electrode 13 is connected to a tubular member 34 of the resonator 32 through the spring clip fingers 34' and capacitively coupled to the cathode by flange 34" insulated from the end wall member 29 by the insulating ring 35, preferably of mica. The other tubular member 33 shields a space between the gap 32' in the resonator 32 and the second accelerator 14. The output may be taken from the output resonator by means of the coupling loop 36.

The press supporting the collector 15 may be protected by overlapping shields 37 supported from the press by means of the support wires 38, and each covering about 120°.

It will thus be seen that in a device made according to my invention the order of the electrode leads is changed and due to the arrangement shown the accelerating electrode may be capacitively coupled directly to the cathode to bring it to ground radio frequency potential, thus making it unnecessary to provide the auxiliary resonator.

While in the arrangement shown a small amount of coupling exists between the grid cathode circuit and the accelerator-cathode circuit, because of the inductance of the length of the grid support which extends beyond the cathode, the design provided is such that this coupling is practically negligible. The tube and circuit shown are for an amplifier but has two instead of the usual three tuned circuits. This is possible because the cathode and the accelerator 13 are brought to the same R-F. potential by flange

34" and the wall 29 with the intermediate insulating member 35.

Because the focusing cylinder 18 encloses both the grid and cathode and is held at cathode potential it serves to focus the electron beam through the tube. This arrangement has the advantage that the focusing electrode is held at fixed voltage instead of the varying voltage of the usual inductive output tube.

10 In Figure 4 is shown the equivalent circuit, the same numerals indicating the same elements as in the other figures.

While I have indicated the preferred embodiments of my invention of which I am now aware and have also indicated only one specific application for which my invention may be employed, it will be apparent that my invention is by no means limited to the exact forms illustrated or the use indicated, but that many variations may 15 be made in the particular structure used and the purpose for which it is employed without departing from the scope of my invention as set forth in the appended claims.

What I claim as new is:

25 1. An electron discharge device having a cathode electrode, grid electrode and another electrode aligned in the order named, said cathode electrode having lead and support conductors, said grid electrode having lead and support conductors extending across but out of contact with the cathode conductors, a cavity resonator coupled between the grid conductors and cathode conductors on the opposite side of the crossed-over portions from said grid electrode and cathode electrode.

30 2. An electron discharge device having an elongated envelope containing a cathode electrode, grid electrode and another electrode arranged along the longitudinal axis of said envelope in the order named, said cathode electrode having radially extending lead-in and supporting conductors, said grid electrode having lead-in and supporting conductors extending across but out of contact with the cathode conductors within said envelope and extending through said envelope, and a cavity resonator coupled between the grid conductors and the cathode conductors on the outside of said envelope.

35 3. An electron discharge device having an envelope and containing in the order named a cathode electrode, grid electrode, accelerator electrode and collector electrode, said cathode electrode being provided with radially extending 40 conducting supporting means extending through the wall of the envelope, said grid electrode being supported on leads extending through but out of contact with said cathode electrode supporting means and through said envelope, said accelerator electrode being provided with conducting supporting means extending radially through the wall of the envelope of said tube, a cavity resonator coupled between the cathode electrode supporting means and said grid leads 45 on the outside of said envelope, and a capacity coupling between said accelerator electrode and said cathode electrode.

4. An electron discharge device having a cathode electrode, a grid electrode, an accelerating electrode and a collector electrode in the order named, said cathode electrode having radially extending leads, said grid electrode having supports and leads extending between but out of contact with said cathode leads, a cavity resonator coupled between the cathode leads and the

grid leads on the other side of the crossed over portions from said cathode and grid electrodes, said accelerator electrode being positioned adjacent said grid electrode, a capacity coupling between said accelerating electrode and said cathode electrode, and an inductive output resonator positioned between said accelerator electrode and said collector electrode.

5. An electron discharge device having an elongated envelope and containing in the order named a cathode electrode, control grid electrode, accelerating electrode and collector electrode, said cathode electrode being provided with a collar-like element coaxial with said cathode electrode, conducting means supporting said cathode electrode from said collar, conducting means extending through said envelope and supporting said collar, said grid electrode having supporting means extending through the supporting means for said cathode electrode and within said collar, the supporting means for said grid electrode extending and sealed through the wall of the envelope of said tube, and a first cavity resonator outside said envelope coupled between the supporting means for said grid electrode and the supporting means for the cathode collar, conducting means supporting said accelerating electrode and sealed through said envelope, a second resonator positioned between said accelerating electrode and said collector electrode and having means contacting the conducting means supporting said accelerator electrode and having a member capacity coupled to the wall of said first resonator adjacent the cathode collar supporting means.

6. An electron discharge device having an elongated envelope and containing in the order named a cathode electrode, grid electrode, accelerator electrode and collector electrode, said cathode electrode having a collar coaxial with said cathode electrode and conducting means extending between said collar and said cathode electrode and supporting said cathode electrode from said collar, said collar being provided with radially extending conducting means extending through and sealed to the wall of the envelope of said tube, conducting means supporting said grid electrode and extending through but out of contact with the supporting means for said cathode electrode and extending through and sealed to the wall of the envelope of said tube, and a coaxial line cavity resonator outside said envelope coupled between the conducting means supporting said grid electrode and the said radially extending conducting means, radially extending conducting means supporting said accelerator electrode extending through and sealed to the envelope of said tube, and a resonator to the envelope of said tube, and a resonator

having a pair of spaced collar-like elements providing a gap, surrounding said envelope, one of said collar-like elements being provided with means contacting the conducting supporting means for said accelerator electrode and having a flange capacity coupled to the coaxial line resonator to capacity couple said accelerator electrode and cathode electrode together.

7. An electron discharge device having a cathode electrode, grid electrode, accelerator electrode and collector electrode arranged in the order named, said cathode electrode comprising a collar and an emitting portion, and conducting means extending between said collar and said emitting portion and supporting said emitting portion from said collar, radially extending conducting means connected to said collar, and said grid electrode comprising a ring-shaped member supporting a foraminous material, and conducting and supporting leads connected to said ring-shaped member and extending through but out of contact with the supporting means for said emitting portion of said cathode electrode, and a resonator outside said envelope having one side coupled to said leads and its other side connected to the radially extending conducting means connected to the cathode collar, and a resonator outside said envelope positioned between the accelerator electrode and the collector electrode and connected to said accelerator electrode, and means capacity coupling said accelerator electrode to said cathode electrode.

8. An electron discharge device having aligned cathode, grid and collector electrodes arranged in that order, said cathode electrode having radially extending supports and leads, said grid electrode having supports and leads extending between but out of contact with said cathode leads, a cavity resonator coupled between the cathode leads and the grid leads on the other side of the crossed-over portions from said cathode electrode and grid electrode, and an inductive output cavity resonator positioned between said grid electrode and said collector electrode.
